UNITED STATES PATENT OFFICE.

JOHN BERG, OF CHICAGO, ILLINOIS, ASSIGNOR TO METAL SPECIALTIES MANUFACTURING COMPANY, OF CHICAGO, ILLINOIS, A CORPORATION OF ILLINOIS.

ELECTRIC CONNECTOR.

1,274,844.

Specification of Letters Patent.

Patented Aug. 6, 1918.

Application filed September 29, 1917. Serial No. 193,889.

To all whom it may concern:

Be it known that I, JOHN BERG, a citizen of the United States, residing at Chicago, in the county of Cook and State of Illinois, have invented a new and useful Improvement in Electric Connectors, of which the following is a specification.

This invention relates particularly to electric connectors of the bayonet-slot type; and the primary object is to provide a plural-socket connector of this type which is simple, cheap and thoroughly adapted to its purpose.

One very important use for the invention is in connection with automobiles, where the dash is usually equipped with an electric connector having a socket adapted to receive the dash-lamp or speedometer-lamp. The plural-socket connector illustrated in the accompanying drawings is adapted to be entered in the dash-carried connector of the machine, and may then carry the dash-lamp and a plug for the spot-light cord, or a plug attached to the cord of an exploring-lamp, according to desire or necessity.

The invention is illustrated in its preferred embodiment in the accompanying drawings, in which—

Figure 1 represents a sectional view of the dash of an automobile equipped with an electric connector provided with a socket, which connector may be of any well-known construction; Fig. 2, a plan view of a plural-socket electric connector embodying my invention, this connector being adapted to a two-wire system; Fig. 3, a view similar to Fig. 2, but showing the sockets of the improved connector in section; Fig. 3^a and Fig. 3^b, end views of the branches of the connector opposite which said figures are located; Fig. 4, a rear end view of the improved connector; Fig. 5, a plan view of one of the contact-members employed; Fig. 6, a section taken as indicated at line 6 of Fig. 3; Fig. 7, a section taken as indicated at line 7 of Fig. 3; Fig. 8, an enlarged broken sectional view of the contact-member shown in Fig. 5; Fig. 9, a view partly in section, showing a connector of modified form, adapted to a single-wire system; Figs. 9^a and 9^b, end views of the branches of the connector shown in Fig. 9, the socket-sleeves being removed; Fig. 10, an end view of the shank of the connector shown in Fig. 9; Fig.

11, a plan view of a contact-member which has a stem exposed at the shank of the connector and branches which make contact with the socket-sleeves with which the branch-arms of the insulating body are equipped; Fig. 12, an edge view of the member shown in Fig. 11; Fig. 13, a plan view of a contact-member which provides the central contacts shown in Fig. 9; Fig. 14, an edge view of the member shown in Fig. 13; Fig. 15, a side elevational view of the connector shown in Fig. 9, with the socket-sleeves removed from the branch-arms of the connector; Fig. 16, a view partly in section, illustrating another modification of the connector which is adapted to connect a one-wire system to a two-wire system, as, for instance, where a car has a single-wire system and it is desired to employ a plug or a lamp having two end contacts; Figs. 16^a and 16^b, end views of the branch arms of the connector shown in Fig. 16, the socket-sleeves being removed; Fig. 17, a plan view of one of the contact-members employed in the construction shown in Fig. 16, this contact-member having a stem exposed at the shank of the connector and plungers projecting freely into the sockets with which the branch-arms of the connector are equipped; Fig. 18, an edge view of the contact-member shown in Fig. 17; Fig. 19, a plan view of the other contact-member employed in the construction shown in Fig. 16, this contact-member having a stem affording a central contact at the end of the shank of the connector and carrying plungers which extend into the sockets with which the connector is provided; Fig. 20, an edge view of the contact-member shown in Fig. 19; and Fig. 21, a side elevational view of the connector shown in Fig. 16, with the socket-sleeves removed from the branch-arms of the connector.

Referring to Figs. 1 to 8, inclusive. A represents the dash of an automobile; B, an electric connector carried thereby, which is equipped with a socket provided with bayonet-slots; and C, an electric connector embodying the invention, which is adapted for use in a two-wire system.

The connector B of the automobile is connected, by conductors 1, 1, with the battery (not shown) of the automobile. Said connector B is fitted with the usual spring-pro-

jected plungers or terminals 2; and the socket 3 of the connector is provided with the usual bayonet-slots 4.

The plural-socket connector C comprises, 5 in this embodiment, a body 5 of the insulating material, which has a shank, or plug-portion, 5^a, and branch-arms, or tenons, 5^b and 5^c; socket-sleeves 6 securely mounted on the tenons, or branch-arms, and provided 10 with bayonet-slots 6^a; and a pair of similar contact-members 7 and 8, each being of the form illustrated in Fig. 6.

The body 5 has at one end a reduced cylindrical portion which forms the shank, or 15 plug-portion, 5^a. This shank is equipped with lateral studs 9 which are adapted to engage the bayonet-slots 4 of the connector B, for illustration. The branch-arms of the body 5 have reduced portions, afford- 20 ing the tenons 5^b and 5^c.

The branch-arms may be provided with 25 sockets, by means of the sleeves 6, which are preferably of metal. These sleeves are securely fastened on the tenons by any suitable means.

The contact-member 7 is preferably of the construction illustrated in Figs. 5 and 8, comprising a stem 7^a, which may be formed of wire; a curved strip, or bar, 7^b; 30 affording arms at one end of the stem 7^a; and spring-projected plungers 7^c mounted on the arms afforded by the member 7^b. One end of the stem 7^a is riveted to an intermediate portion of the head, or strip, 7^b. 35 The other end of said stem is upset, forming an enlargement 7^d, adapted to afford a contact at one end of the shank 5^a of the connector.

The spring-projected plungers 7^c are tele- 40 scopically mounted in tubular members 7^e, which have rivet-portions at one end which extend through perforations in the member 7^b and are firmly riveted to said member. The member 7^b is bent, or curved, so that 45 the spring-projected plungers 7^c mounted thereon will diverge or form an angle corresponding with the Y formed by the branch arms of the body 5. The members 7^e afford contacts which project beyond the ends of 50 the tenons 5^b and 5^c into the socket-sleeves 6, as clearly shown in Fig. 3.

The contact-member 8 is of the same construction as the contact-member 7. The corresponding parts are designated by the 55 numeral 8 with indices corresponding with those employed in connection with the numeral 7.

The body 5 may be composed of a hard rubber composition, or other suitable insulating material, the body being preferably molded with the contact-members 7 and 8 in position, so that they will be firmly embedded in the body 5.

It now will be understood that the shank 5^a of the connector C may be entered in the

socket of the connector B, and the contacts 7^d and 8^d exposed at the end of the shank 5^a will contact with the spring-projected plungers 2 of the connector B. Connector-plugs, or lamps, may be carried by the 70 sockets 6, as desired. For instance where a plural-socket connector C is mounted on a dash-carried connector, a dash-lamp may be mounted in one of the sockets 6, while the other socket may receive the plug of a spot 75 light cord, or an exploring-lamp cord.

In the modification illustrated in Figs. 9 to 15, inclusive, C' represents the improved connector. In this form, the connector comprises an insulating body 10 having a plug-portion, or reduced shank 10^a and having branch-arms 10^b and 10^c which are reduced to afford tenons; a pair of socket-sleeves 11 securely fastened on said tenons and provided with bayonet-slots 11^a; a contact-member 12 of the form shown in Figs. 11 and 12; and a contact-member 13 of the form shown in Figs. 13 and 14.

The contact-member 12, in the form shown, is of Y-shape, having a stem 12^a and branches 12^b and 12^c. The contact-member 12 is embedded in the body 10 near one side thereof, and has the stem 12^a exposed at one side of the plug-portion 10^a of the connector, and has the branches 12^b and 12^c exposed at one side of the tenons 10^b and 10^c of the connector. Thus, the stem 12^a is adapted to contact with a socket-sleeve of a connector mounted on a machine provided with a one-wire system; and the branches 12^b and 12^c are adapted to contact with the socket-sleeves 11.

The construction of the contact-member 13 is similar to the construction of the contact-member 7. Thus, the contact-member 13 has a central stem 13^a, a cross-member 13^b riveted on one end thereof and affording arms, tubular members 13^e riveted to the arms of the member 13^b, and spring-projected plungers 13^c mounted in the members 13^e. One end of the stem 13^a is upset to form the contact 13^d.

The body 10 is preferably molded of a suitable insulating compound, the contact-members being embedded therein in the molding operation. The shank 10^a of the body 10 is equipped with lateral studs 14 adapted to engage the bayonet-slots of the socket of a connector mounted on the dash of an automobile, for illustration.

The connector C', as described, is adapted to be entered in the socket of a connector provided with a single central contact, and the sockets 11 are adapted to receive plugs, or lamps, provided with a single central contact.

In the modification shown in Figs. 16 to 21, inclusive, C² represents a plural-socket connector adapted to connect lamps, or plugs, having two end contacts with a connector 130

having a single end contact. In this form, the connector comprises a body 15 of insulating material, having a cylindrical plug-portion, or shank, 15^a, and tenoned branch-arms 15^b and 15^c; a pair of socket-sleeves 16 mounted on the branch-arms and provided with bayonet-slots 16^a; a contact-member 17 of the form shown in Figs. 17 and 18; and a contact-member 18 of the form 10 shown in Figs. 19 and 20.

The contact-member 17 preferably comprises a strip of metal affording a stem 17^a and a head 17^b; and spring-projected plungers 17^c mounted in tubular members 17^d which have one end riveted to the head 17^b. As shown and described, the stem 17^a is offset from the plane of the plungers 17^c, so that the plungers 17^c are adapted to project from the ends of the tenons 15^b and 15^c into 20 the socket-sleeves 16 in the manner shown in Figs. 16^a and 16^b, while the stem 17^a is adapted to be exposed at one side of the reduced shank 15^a, as shown in Fig. 16.

The contact-member 18 is similar in construction to the contact-member 17, but has its stem offset in the manner shown in Fig. 20. Thus, the contact-member 18 comprises a stem 18^a having an upset end affording a contact-member 18^d; a head, or bent strip, 30 18^b, riveted to the opposite end of the stem 18^a and affording arms; tubular members 18^c having one end riveted to the arms afforded by the member 18^b; and spring-projected plungers 18^e mounted in the members 18^c. The stem 18^a is offset from the plane of the plungers 18^e; and the contact-member 18 is so embedded in the insulating body 15 as to have the contact 18^d exposed centrally at the end of the shank 15^a, while the plungers 40 18^e project from the ends of the tenons 15^c into the sockets 16, as will be understood from Figs. 16^a, 16^b and 21.

Thus, the connector C² is adapted to receive in the sockets 16 plugs, or lamps, having two end-contacts, while the shank of the connector is adapted to enter the socket of a connector having a single end-contact. The shank 15^a is equipped with lateral studs 19 adapted to engage the bayonet-slots of 50 such connector as the connector C² may be mounted upon, as, for instance, the connector of a car having a single-wire system.

Where the improved connector is adapted to receive two plugs, as in the forms illustrated, the Y-form of connector is desirable. The form may be varied to meet conditions, however.

The construction described is simple, cheap and admirably adapted to its purpose. 60 The foregoing detailed description has been given for clearness of understanding only, and no unnecessary limitation should be understood therefrom, but the appended claims should be construed as broadly as 65 permissible in view of the prior art.

What I regard as new, and desire to secure by Letters Patent, is:

1. In an electric connector, a body of insulating material having a socket-entering shank at one end and branching tenons at 70 the other end, sleeves on said tenons provided with bayonet-slots, bayonet-slot-engaging studs on said shank, and a contact-member in said body having a stem embedded in and serving as a contact for said 75 shank and having branches embedded in and serving as contacts for said tenons.

2. In an electric connector, a body of insulating material having a socket-entering, stud-equipped shank at one end and arms 80 branching from the other end, sockets carried by said arms equipped with bayonet-slots, and a contact-member embedded in said body having a stem substantially embedded in and serving as a contact for said 85 shank and having arms substantially embedded in said first-named arms and plungers mounted on said second-named arms projecting freely into said sockets.

3. In an electric connector, a body of insulating material having a socket-entering stud-equipped shank at one end and arms branching from the other end, sockets carried by said arms equipped with bayonet-slots, and a pair of contact-members embedded in said body, each contact-member having a stem substantially embedded in and serving as a contact for said shank and having branches substantially embedded in the arms of said body, the branches of at 100 least one of said contact-members carrying spring-projected plungers affording end-contacts.

4. In an electric connector, a Y-shape insulating body having a plug-portion of cylindrical form equipped with lateral studs and having arms serving as tenons, socket-sleeves carried by said arms provided with bayonet-slots, and a pair of Y-shape contact-members substantially embedded in said 105 body, one of said contact-members at least having a stem with an end affording a contact at the end of said plug-portion and having arms and spring-projected plungers mounted thereon and extending freely into 110 said socket-sleeves.

5. In an electric connector, an insulating body provided with a cylindrical plug-portion equipped with bayonet-slot-engaging studs and provided with arms, socket-sleeves 120 mounted on said arms and provided with bayonet-slots, and a pair of contact-members substantially embedded in said body, one of said contact-members having a stem exposed at one side of the plug-portion of said 125 body and having branches in said arms, and the other contact-member having a stem extending through the plug-portion of said body and affording an end-contact and having branches in the arms of said body 130.

equipped with spring-projected plungers extending freely into said socket-sleeves.

6. In an electric connector, an insulating body having a cylindrical plug-portion equipped with lateral studs and having branch-arms, socket-sleeves mounted on said arms and provided with bayonet-slots, and a pair of contact-members substantially embedded in said body, one of said contact-members having a stem exposed at one side of the plug-portion of said body and having branches equipped with spring-projected plungers projecting freely into said socket-sleeves, and the other of said contact-members having a stem extending through the

plug-portion of said body and affording an end-contact and having branches equipped with spring-projected plungers extending freely into said socket-sleeves.

7. In an electric connector, a contact-member adapted to be embedded in an insulating body, said contact-member comprising a stem having one end adapted to serve as a contact, a bent cross member permanently secured to the other end of said stem, divergent tubular members secured to the end portion of said bent member, and spring-projected plungers mounted in said tubular members.

JOHN BERG.
